C. FINKBEINER

APPARATUS FOR AND METHOD OF STRAIGHTENING DISK WHEELS

Filed Aug. 17, 1923

INVENTOR.

CHARLES FINKBEINER.

BY

C.B. Leyland

ATTORNEY.

WITNESS:-

Walter M. Grout.

UNITED STATES PATENT OFFICE.

CHARLES FINKBEINER, OF PHILADELPHIA, PENNSYLVANIA, ASSIGNOR TO BUDD WHEEL COMPANY, OF PHILADELPHIA, PENNSYLVANIA, A CORPORATION OF PENNSYLVANIA.

APPARATUS FOR AND METHOD OF STRAIGHTENING DISK WHEELS.

Application filed August 17, 1923. Serial No. 657,853.

To all whom it may concern:

Be it known that I, CHARLES FINKBEINER, a citizen of the United States, residing at Philadelphia, Pennsylvania, have 5 invented certain new and useful Improvements in Apparatus for and Method of Straightening Disk Wheels; of which I declare the following to be a full, clear, and exact description.

10 My invention relates to an improved method of and apparatus for straightening disk wheels. It sometimes happens that, as a result of accidents, metal disk wheels in use on automobiles are bent or buckled so 15 that they will no longer run true. It is important to provide some method of straightening such wheels so as to restore them to their normal shape. The usual method of straightening, by means of dies 20 in a press, is slow and costly and requires equipment which is too expensive for the service station or garage. The object of my present invention is to provide a method of straightening metal disk wheels which is 25 cheap and quick and does not require elaborate or expensive equipment, so that it may be used effectively by the smallest garages and service stations.

Further objects, and objects relating to 30 detail and economies of operation, will definitely appear from the detailed description to follow. In one instance, I accomplish the objects of my invention by the method set forth in the following specification. 35 My invention is clearly defined and pointed out in the appended claims. In the single figure of the drawing, forming a part of this specification, I have illustrated an apparatus and its use in carrying out my improved method of straightening disk wheels.

40 My invention consists in clamping the hub portion of the wheel on a suitable support and applying pressure to the periphery of the wheel in a direction parallel to its axis. The pressure is to be applied in the direction necessary to return the buckled or distorted portion of the wheel to normal; that is, if a portion of the wheel is bent 45 outwardly, the pressure is applied to the outer edge of the rim, and, if the wheel is buckled inwardly, the pressure is applied to the inner edge of the rim. In either case,

the pressure is applied in a direction parallel to the axis of the wheel. 55

The apparatus illustrated in the drawing constitutes a convenient means for carrying out my invention. This apparatus consists of a press, 10, having a table, 11, on which is mounted a block, 12, of about the diameter of the hub portion of the wheel. A collar or washer, 13, having an external diameter equal to the diameter of the central opening in the disk wheel, is mounted on top of block, 12. The wheel rests on the 60 block, 12, with the portion of the disk adjacent the central opening in contact with the upper surface of the block and the collar or washer, 13, fitting in said central opening. The wheel is clamped on said table by 65 the bolt, 14, passing through table, 11, block, 12, washer, 13, and a clamping plate, 15, which engages the hub portion of the disk. The nut, 16, screwed on the end of bolt, 14, clamps the disk between the block, 70 75 and plate, 15.

The disk wheel, 21, is shown clamped in the press by the means just described. It is to be noted that the wheel is clamped at the hub portion and the rest of the disk is free. 80 The dotted lines indicate, at 22, a part of the disk which has been bent or buckled from its normal shape. In this particular instance, the wheel is buckled outwardly and the pressure is applied to the outer edge of 85 the wheel rim, 24, by means of ram, 17, having a rack, 18, meshing with a pinion, 19, which is rotated by the handle, 20. It is to be noted that the axis of block, 12, is parallel to the line of travel of ram, 17. This is 90 important because the pressure should be applied to the periphery of the wheel in a direction parallel to the axis of the wheel.

The operator clamps the wheel at the hub portion of the disk, for instance, by the 95 clamping bolt and plate on the table of the press. He rotates the disk to bring a buckled portion in line with the ram, 17, and applies pressure at such point by means of the ram. This is repeated at the buckled points 100 until the wheel is restored to its normal shape. In case the wheel is buckled in both directions, pressure is applied at the periphery to bring the portions buckled in one direction back to normal and then the disk is 105 reversed and clamped in reversed position

and peripheral pressure applied in a direction parallel to the axis of the wheel to bring back to normal the parts buckled in the opposite direction.

5 I am aware that the method described may be varied considerably without departing from the spirit of my invention, and, therefore, I claim my invention broadly, as indicated by the appended claims.

10 Having thus described my invention, what I claim as new and useful and desire to secure by Letters Patent is:

11 1. A machine of the character described comprising an arbor press having a horizontal base and an overhanging portion, said base having a portion extending forwardly therefrom, a vertically extending ram mounted on said overhanging portion adapted for reciprocatory movement toward and from 15 said base, a wheel center clamp secured to the outer end of said forwardly extending portion of the base adapted to clamp a wheel in a substantially horizontal plane whereby to present the rim thereof between said ram and said base, and operating means for said ram mounted on said overhanging portion.

20 2. A machine of the character described comprising a press having a horizontally extending base, a member disposed above said base and extending substantially parallel thereto, a vertically extending ram mounted on said member adapted for relative movement with respect to said base, a wheel center clamp secured to said base adapted to 25 clamp a wheel in a substantially horizontal plane whereby to present the rim thereof between said ram and base thereof at an eleva-

tion considerably above said base, and operating means for effecting relative movement between said ram and said base.

40 3. The method of straightening distorted disk wheels in which the central portions of the disk are provided with trued faces for alignment and clamping of the disk flat-wise on the wheel hub flange, which method consists in supporting the wheel from its trued central portion with the portion exterior to said trued portion extending laterally free of the support, clamping in a fixed plane and rigidly against distortion substantially the 45 entire area comprehended by said trued faces for engagement with the wheel hub flange, and while the wheel is so clamped directing bending pressures on the distorted free portions of said wheel on lines substantially parallel to the wheel axis.

50 4. The method of straightening distorted metallic disk wheels, which method consists in supporting the central portions of said wheels in a substantially horizontal plane 55 with the outer peripheral portions thereof extending laterally free of the support, clamping rigidly against distortion substantially the entire area comprehended by said 60 central portion, and applying a pressure 65 upon the distorted free portions of said wheels in directions substantially parallel to the wheel axis until the distorted portions of the wheel are bent sufficiently to give a permanent set in the normal plane upon the release of the applied pressure.

70 In testimony whereof, I affix my signature.

CHARLES FINKBEINER.
